FRAME AND HANDLE ASSEMBLAGE FOR
MIRRORS, BRUSHES, AND OTHER DEVICES
FORMING PARTS OF TOILET AND DRESS-
ER SETS

William Steinen, South Orange, N. J.

Application April 7, 1939, Serial No. 266,497

2 Claims. (Cl. 88—102)

The present invention relates to a frame and handle assemblage for mirrors, brushes and other devices forming parts of toilet and dresser sets.

It is among the objects of the present invention to provide an improved frame and handle assemblage for mirrors, brushes and other devices forming parts of toilet and dresser sets which will involve a few parts, which will be of artistic, durable and inexpensive construction and which, at the same time, may be manufactured at a minimum of expense by relatively unskilled labor.

Another object is to provide an improved frame and handle assemblage of the character above described which may be inexpensively manufactured of sheet metal or die cast metal parts, with assurance that the construction will be rigid and durable and may be subjected to rough usage over long periods of time without tending to separate, becoming loose at the throat or becoming dismantled.

Still further objects and advantages will appear from the more detailed description set forth below, it being understood, however, that this more detailed description is given by way of illustration since various changes therein may be made by those skilled in the art without departing from the scope and spirit of the invention.

In accomplishing the above objects, it has been found most suitable to form the frame member of a substantially continuous metal strip of U-cross section, which metal strip may be split adjacent the throat where it is joined to the end of the handle.

Although the handle may be made of various constructions, in the embodiment shown, it is formed of a die casting which may be of suitable ornamental shape.

In the preferred construction, the mirror or brush back is provided with a metal or other backing plate having a rod extension which may be threaded and which may extend into an opening or bore in the throat portion of the handle adjacent the junction of the frame with the handle.

This throat portion may be caused to draw up the frame on the handle to cause a rigid connection therebetween and to latch with the terminal portions of the rim member encircling the mirror and brush back, as the case may be.

In a preferred form of the invention, the threaded rod is caused to extend through an opening in the handle where a nut is positioned, said nut being readily accessible from the outside of the handle and being designed to draw it up

and cause a tight connection between the frame and the handle construction.

In an alternative construction, a flared throat portion is provided which may contact the continuous metal strip forming a peripheral channel rim and this throat member may have a socket to receive a handle.

Between the contact with the channel rim and the socket for receiving the handle, there may be positioned a take-up bolt connected to the backing plate of the mirror or brush back provided with a nut to permit tightening up of the entire construction.

Referring to the drawing which illustrates several of the various possible embodiments of the present invention, but to which the present invention is by no means restricted since the drawing is merely by way of illustration and not by way of limitation,

Figure 1 is an elevation showing the complete assemblage of the frame and handle with a portion of the frame adjacent the handle being broken away more clearly to show the construction.

Figure 1—*a* is a fragmentary transverse sectional view along the line 1—*a*—1—*a* of Figure 1.

Figure 2 is a fragmentary transverse sectional view of the construction between the frame and the handle upon enlarged scale as compared to Figure 1 and on the line 2—2 of Figure 1.

Figure 3 is a fragmentary transverse sectional view showing the assemblage between the frame and the handle upon the line 3—3 of Figure 2 upon an enlarged scale as compared to Figure 1.

Figure 3—*a* is a fragmentary transverse sectional view along the line 3—*a*—3—*a* of Figure 3.

Figure 4 is a fragmentary side sectional view of an alternative construction upon a reduced scale as compared to Figures 1 and 3.

Referring to the construction as shown in Figure 1, the frame A, which in the embodiment shown embraces a mirror or brush back B, may also, if desired, embody a mirror or other suitable device useful in connection with a toilet set assemblage.

The handle construction C is provided with a suitable arrangement D to lock it to the frame A and mirror and brush back B.

Referring to Figures 1, 1—*a*, and 2, the channel rim frame is of U-shape cross section and has the side flanges 10 and 11 together with the base flange 12 which has the projecting portions or ridges 13 so as to form a groove or channel 14.

The channel member A may be bent to oval shape, as indicated upon Figure 1.

The front side flange 10 of the channel rim A may contact the bevelled portion 15 of the mirror B which mirror is provided with a backing 16, the metal stiffener 17, the backing or cardboard 18 and the ornamental back 19, all have the same outline as the frame.

The edge of the ornamental backing is held against the backing 18 by means of the flange 10 of the U or V cross section channel rim member A.

The portion of the back metal plate 17 adjacent the throat T may be cut away or recessed at 20a and welded at 20b to the metal strip or bar 20, which continues into the rod member 21 having the threaded portion 22.

The handle may be of cast metal or formed of a plastic material and is provided with a series of piercings 23, an ornamental end portion 24 and the outstanding ear portions 25.

The outstanding ear portions 25 ride in the recess 14 between the bosses 13 and they also are provided with protuberances or bosses 26 which fit into the holes 27 in the portions of the channel A adjacent the throat T.

Extending into the uppermost piercing 28 in the handle C are the bores 29 and 30 which receive the threaded rod 22. The piercing 28 receives the nut 32 forming part of the assemblage structure D.

The nut 32 is designed to abut and closely fit at 33 and 34, the flat surfaces 35 and 36 on bosses 30 at the top and bottom of the piercing 28.

It will be noted that the channel rim A terminates at 40 and the terminal edge portions are overlapped by U-shaped member or clip 41 which is curved, as indicated at 42, to conform to the bottom of the frame A and recess 42a in the upper end of the handle and which has the indentations 43 fitting into the openings 44 in the edges of the channel member A.

The sides 41a of the U-shaped clip 41 fit along the front of the mirror B and the ornamental backing 19 to form a complete assemblage.

In assembling the device of the present invention, the U-shaped channel rim member A may be fitted around the mirror B, the backing 16, the metal plate 17, the backing 18 and the ornamental back facing 19.

The clip 41 may be then placed across the terminal end portions 40 of the rim channel member A with the threaded rod 22 projecting through the opening 41b in the base 42 thereof. The threaded extension 22 then may be inserted into the openings 29 and 30 in the throat portion T of the handle C.

Before this is done, the nut D is placed between the faces 35 and 36 of the opening 28, and it is then tightened up upon the threaded rod 22 to draw up the extensions 25 of the handle along the channel 14 between the elevations 13.

When the combination is completed, the projections 43 on the base of the clip 41 will fit into the recess 44 in the rim A while the tits 26 on the handle extensions 25 will fit into the recesses 27 in the rim A.

The resultant construction, as formed, is strong and durable and will not tend to loosen even though the assemblage be subjected to considerable handling.

In the alternative construction shown in Figure 4, the backing plate 17' is spot welded to the upper portion 20' of the rod element 21'. The rod element 21' is threaded at 22' and projects through an opening 29' in the throat member T'.

The throat member T' is provided with a flar-

ing upper portion 25' which contacts the channel rim 10' at the points 26'.

When the nut D' is tightened up on the rod 22, it will draw up the throat 25' upon the channel rim member 10' tightening up the entire construction.

The handle C' has a reduced diameter portion 60 which fits into the socket 61 in the bottom of the throat member T'.

10 The handle construction C', of course, may be varied so as to be made of wood or it may be made of a casting, as indicated at C in Figure 1, or it may be made of various sheet metal constructions as illustrated in my Patents Nos. 2,136,643; 2,136,644; 2,136,645; 2,139,564; 2,139,565; 2,136,646 and 2,151,449.

15 The mirror or brush back construction B, the backing plate 17 and the backing facing 19 may also be made of the form and shape, as shown in said patents.

20 It is apparent the specific illustrations above shown have been given by way of illustration and not by way of limitation and that the structures above described are subject to wide variation and modification without departing from the scope or intent of the invention all of which variations and modifications are to be included within the scope of the present invention.

25 What is claimed is:

1. In a mirror, brush or similar construction, a frame and handle assemblage to receive a mirror or brush element comprising a split resilient sheet metal channel rim and U-shaped cross section constituting the periphery of the frame, a separate handle member having a throat portion connected to said frame at the split in said channel rim, a backing member having an enlarged portion of the same shape and outline as the mirror and back of the brush element, the edges of said mirror or brush element and said backing member being tightly held within said channel rim and between the side flanges and drawn tightly up and resiliently wedged between said side flanges, said handle member being provided with an axial bore adjacent the frame and said backing member being provided with a threaded extension extending into said bore, said handle member being laterally pierced and said piercing being provided with parallel upper and lower faces and an elongated nut member fitted into said piercing also having upper and lower parallel end faces closely abutting the faces of said piercing and threaded upon said threaded extension and serving to draw up said handle upon said frame.

2. In a mirror, brush or similar construction, a frame and handle assemblage to receive a mirror or brush element comprising a split resilient sheet metal channel rim and U-shaped cross section constituting the periphery of the frame, a separate handle member having a throat portion connected to said frame at the split in said channel rim, a backing member having an enlarged portion of the same shape and outline as the mirror and back of the brush element, the edges of said mirror or brush element and said backing member being tightly held within said channel rim and between the side flanges and drawn tightly up and resiliently wedged between said side flanges, said handle member being provided with an axial bore adjacent the frame and said backing member being provided with a threaded extension extending into said bore, said handle member being laterally pierced and said piercing being provided with parallel upper and lower faces and an elongated nut member fitted into said piercing also having upper and lower parallel end faces closely abutting the faces of said piercing and threaded upon said threaded extension and serving to draw up said handle upon said frame.

3. In a mirror, brush or similar construction, a frame and handle assemblage to receive a mirror or brush element comprising a split resilient sheet metal channel rim and U-shaped cross section constituting the periphery of the frame, a separate handle member having a throat portion connected to said frame at the split in said channel rim, a backing member having an enlarged portion of the same shape and outline as the mirror and back of the brush element, the edges of said mirror or brush element and said backing member being tightly held within said channel rim and between the side flanges and drawn tightly up and resiliently wedged between said side flanges, said handle member being provided with an axial bore adjacent the frame and said backing member being provided with a threaded extension extending into said bore, said handle member being laterally pierced and said piercing being provided with parallel upper and lower faces and an elongated nut member fitted into said piercing also having upper and lower parallel end faces closely abutting the faces of said piercing and threaded upon said threaded extension and serving to draw up said handle upon said frame.

lower faces and an elongated nut member fitted into said piercing also having upper and lower parallel end faces closely abutting the faces of said piercing and threaded upon said threaded extension and serving to draw up said handle upon said frame, said throat portion of said

5 handle member being provided with wings and said channel rim member being provided with a central groove, said wings being designed to fit in and slide in said groove to draw said frame up upon said handle.

WILLIAM STEINEN.
